CLOSURE

Anthony F. Ciarfello, Albany, N. Y.

Application January 18, 1945, Serial No. 573,403

2 Claims. (Cl. 138—89)

1

My invention relates to closures and particularly to improved closures for pipes and the like.

Traps in soil pipes, for example, are usually closed by an end ferrule which is calked into the bell end of the trap and which is internally threaded to receive a closure plug.

When it is necessary to open the trap the plug must be removed but in most cases it is impossible to loosen the plug without breaking the ferrule. Filling pipes leading to oil or other storage tanks are closed either by an end plug or cap and in many cases these are very difficult to remove. Furthermore, the threads thereon are frequently damaged making it impossible to use the part having the damaged thread.

The general object of my invention is to provide a closure for pipes and the like which can be easily opened or removed and which will at all times provide a substantially air tight seal. Another object is to provide a device of this character adapted to replace the ordinary end ferrule and plug now employed in the traps of soil pipes and which is easily removable and may be replaced after removal to provide an air tight closure of the trap. Another object is to provide a device of this character which is adapted for general application to all kinds of pipes to form an air tight closure for the ends thereof and which is easily removable.

I accomplish these objects by means of the novel elements and the combinations and arrangements thereof described below and illustrated in the accompanying drawings in which—

Fig. 1 is a vertical cross section of my device in a form adapted for application to the trap in a soil pipe;

Fig. 2 is a fragmentary elevation view, partially in section, showing the exterior fastening means of my closure;

Fig. 3 is a fragmentary top plan view of my device, partially in section, showing the exterior fastening means;

Fig. 4 is a fragmentary bottom view of the cover, partially in section;

Fig. 5 is a fragmentary top plan view, partially in section, of the tubular element shown in Fig. 1 with the cover removed;

Fig. 6 is a fragmentary elevation view partially in section and with portions broken away, of a trap showing my closure element therein;

Fig. 7 is a vertical cross section of a modified form of closure adapted for use on the threaded end of a pipe; and

Fig. 8 is a section of Fig. 7 in the plane 8—8.

Referring to the drawings—

2

My device comprises a tubular element such as 1, here illustrated as an end ferrule, which is provided at the bottom with a peripheral ledge 2 adapting it to be secured in the bell 3 of a trap by means of calking 4. Instead of being interiorly threaded at the top, as in the case of end ferrules of the present type, the tubular element 1 adjacent the upper end thereof is provided with an inwardly projecting lug 5 having the bottom surface 6 thereof upwardly inclined toward the axis of the element 1. At the upper end, the walls of the element 1 are preferably thickened slightly as shown at 7 and the extreme end of the element is provided with an annular projection 8, the outside diameter of which is slightly less than the outside diameter of the element 1 at the top so as to provide a narrow annular shoulder 9 on the outside of and below the projection 8. The cover 10 for the end of the element 1 is preferably slightly crowned on the top and is provided on the bottom with an annular recess 11 adapted to receive the annular projection 8 on the element 1 with a gasket 12 positioned in the bottom of the recess. The cover, on the bottom, is also provided with a depending lug 13 adapted to underlie the lug 5 on the element 1 and in spaced relation thereto when the cover is in place. A set screw 14 passes through a threaded hole in the lug 13 and sets against the inclined bottom of the lug 5. Thus by adjusting the set screw 14 the distance between the lugs 5 and 13 may be varied and by properly adjusting the set screw 14 a firm air tight contact is formed by pressure on the gasket 12.

The side of the element 1, in a zone substantially diametrically opposed to the lug 5, is provided with a pair of circumferentially spaced ears 15, and the threaded member 16 is secured between the ears 15 by means of the pin 17.

The cover 10, in a zone substantially diametrically opposite the lug 13, is also provided with a pair of outwardly-extending, spaced ears 18 adapted to receive the threaded element 16 therebetween, and a wing nut 19 cooperating with the threaded element 16 serves to clamp the cover tightly against the gasket 12.

In order to remove the cover it is merely necessary to loosen the wing nut 19 so that the threaded element 16 with the loose wing nut thereon may be swung outwardly on the pin 17 as a hinge whereupon the cover may be removed by tilting it or turning it until the set screw 14 moves out of engagement with the lug 5. To replace it the cover is tilted and the lug 13 is pushed under the lug 5 until the end of the set screw 14

comes into contact with the bottom of the lug 5. In order to insure a tight joint the set screw should be so adjusted that the portion of the cover diametrically opposite the lug 13 does not quite seat itself. Thus, when the threaded element 16 with the loose wing nut thereon is swung up between the ears 18 and the wing nut tightened the cover may be forced downwardly to a firm seat all around on the gasket 12.

The modified device shown in Figs. 7 and 8 is substantially the same as that just described except that the tubular element 20 is internally threaded, as shown at 21, adapting it to be screwed on to the threaded nut of a pipe and, to facilitate this operation the exterior of the element 20 is provided with spaced lugs 22 adapted to engage the jaws of a wrench to prevent it from slipping. The interior of the element 20 adjacent the upper end thereof is provided with an inwardly projecting lug 23 similar to the lug 5 described above. The cover 24 is preferably slightly crowned on the top, as shown, and is provided on the bottom with a downwardly and outwardly extending lug 25 adapted to underlie the lug 23 in spaced relation thereto when the cover is in place. A set screw 26 which is threaded through the lug 25 sets against the sloping bottom of the lug 23 and functions in the same way as the set screw 14 just described. The top end of the element 20 and the bottom of the cover are provided with complementary interfitting annular portions having the annular gasket 27 positioned therebetween. Ears 28 similar to the ears 15 are cast on the element 20 and the threaded element 29 is pivotally secured between the ears by means of the pin 30. Spaced ears 31 are also provided on the cover 24 between which the threaded element 29 passes and wing nut 32 serves to clamp the cover in place tightly against the gasket.

From the foregoing it will be apparent that I have provided an air tight closure of the character described which is easily removable and easily replaceable. The gasket may be cemented in the cover groove and, if the gasket should become compressed to substantially less than its original thickness, such reduced thickness may be compensated for by adjusting the set screw 14 so that an air tight joint is always provided. The set screw bearing against the bottom of the lug on the tubular element forms therewith a hinge-like structure which, when the set screw is properly adjusted, as pointed out above, causes those portions of the cover adjacent thereto to fit tightly against the top of the tubular element when the oppositely disposed portions of the cover, adjacent the clamping means, are drawn into tight contact with the top of said tubular element by manipulating said clamping means.

What I claim is:

1. An end ferrule comprising a tubular element open at the top and the bottom thereof; and provided with only a single, inwardly-projecting lug on the inside adjacent the top edge thereof, a

cover for the top of said tubular element having on the bottom and adjacent the edge thereof a depending, outwardly-projecting lug adapted, when said cover is in place, to underlie said lug on said tubular element in spaced relation thereto, a set screw extending through in threaded cooperation with one of said lugs and having the end thereof bearing against the other of said lugs to form a hinge-like structure, and clamping means operable from the exterior of said ferrule and cooperating with said cover and said tubular element in a zone substantially opposite said lugs for securing said cover to said tubular element; whereby, by adjusting said set screw, said cover 10 may be positioned on said tubular element with the portions of said cover adjacent said set screw in contact with the top of said tubular element and the oppositely-disposed portions of said cover adjacent said clamping means in slightly spaced 15 relation to the top of said tubular element; and all portions of said cover may then be brought into tight contact with the top of said tubular element by tightening said clamping means.

2. An end ferrule comprising a tubular element 25 open at the top and bottom thereof; and provided with only a single, inwardly-projecting lug on the inside adjacent the top edge thereof, the lower surface of said lug being upwardly inclined towards the axis of said tubular element, a cover 30 for the top of said tubular element having on the bottom and adjacent the edge thereof a depending, outwardly-projecting lug having the upper surface thereof downwardly inclined from the axis of the tubular element, and adapted, when 35 said cover is in place, to underlie said lug on said tubular element in spaced relation thereto, a set screw extending through in threaded cooperation with one of said lugs and having the end thereof bearing against the other of said lugs to form a 40 hinge-like structure, and clamping means operable from the exterior of said ferrule and cooperating with said cover and said tubular element in a zone substantially opposite said lugs for securing said cover to said tubular element; whereby, by adjusting said set screw, said cover may be positioned on said tubular element with the portions of said cover adjacent said set screw in contact with the top of said tubular element and the oppositely-disposed portions of said cover adjacent said clamping means in slightly spaced 45 relation to the top of said tubular element; and all portions of said cover may then be brought into tight contact with the top of said tubular element by tightening said clamping means.
